UNITED STATES PATENT OFFICE.

GUSS A. SWANSON, OF CHICAGO, ILLINOIS.

DESIGN FOR A CLOTHES HOOK.

Application filed February 6, 1922. Serial No. 571. Term of patent 14 years.

To all whom it may concern:

Be it known that I, GUSS A. SWANSON, a citizen of the United States, residing at Chicago, in the county of Cook and State of Illinois, have invented a new, original, and ornamental Design for Clothes Hooks, of which the following is a specification, reference being had to the accompanying drawing, forming part thereof.

The figure is a plan view of clothes hook arranged for wall or ceiling use, showing my new design.

I claim:

The ornamental design for a clothes hook, as shown.

GUSS A. SWANSON.
